US00D716833S

(12) **United States Design Patent**
Donahue et al.

(10) **Patent No.:** **US D716,833 S**
(45) **Date of Patent:** ** *Nov. 4, 2014

(54) **DISPLAY SCREEN WITH GRAPHICAL USER INTERFACE**

(71) Applicant: **Microsoft Corporation**, Redmond, WA (US)

(72) Inventors: **Megan Donahue**, Seattle, WA (US); **Chad Michael Roberts**, Snohomish, WA (US); **Rhoniel Villano Manlapaz**, Fullerton, CA (US)

(73) Assignee: **Microsoft Corporation**, Redmond, WA (US)

(*) Notice: This patent is subject to a terminal disclaimer.

(**) Term: **14 Years**

(21) Appl. No.: **29/440,593**

(22) Filed: **Dec. 21, 2012**

(57) **CLAIM**

The ornamental design for a display screen with graphical user interface, as shown and described.

DESCRIPTION

The FIGURE is a front view of a display screen with graphical user interface showing a new design shown on a device. The broken line showing of the remainder of the graphical user interface and the remainder of the device is for environmental purposes only and forms no part of the claimed design.

1 Claim, 1 Drawing Sheet
